UNITED STATES PATENT OFFICE.

MAURICE LEIGH, OF CHICAGO, ILLINOIS.

DESIGN FOR A DISPLAY FRAME.

Application filed July 5, 1928. Serial No. 27,393. Term of patent 14 years.

To all whom it may concern:

Be it known that I, MAURICE LEIGH, a citizen of the United States, residing at Chicago, in the county of Cook, and State of Illinois, have invented a new, original, and ornamental Design for Display Frames, of which the following is a specification, reference being had to the accompanying drawing, forming part thereof.

The figure is a front elevation of a display frame showing my new design.

I claim:

The ornamental design for a display frame, as shown.

MAURICE LEIGH.
